[57] CLAIM

The ornamental design for a toaster, as shown and described.

DESCRIPTION

FIG. 1 is a perspective view of the design for a toaster of the present invention;

FIG. 2 is a front plan view of the toaster design of the present invention;

FIG. 3 is a side view of the toaster design of the present invention;

FIG. 4 is a rear plan view of the toaster design of the present invention;

FIG. 5 is a second side view of the toaster design of the present invention;

FIG. 6 is a top view of the toaster design of the present invention;

FIG. 7 is a bottom view of the toaster design of the present invention;

FIG. 8 is a perspective view of the toaster design of the present invention showing the side doors open;

FIG. 9 is a second embodiment of the toaster, the top and bottom views being substantially similar except for the absence of the handle and control buttons and slightly larger side doors. The rear view is identical to FIG. 4; and,

FIG. 10 is a perspective view of the embodiment of FIG. 9, showing the doors in an open position.
